SEAT FOR A TRANSIT VEHICLE

Chester J. Barecki, Grand Rapids, Mich, assignor to
American Seating Company, Grand Rapids, Mich.

Filed May 14, 1973, Ser. No. 360,020

Term of patent 14 years

Int. Cl. D6—01

U.S. Cl. D6—48

FIG. 1

FIG. 2

FIG. 3

FIG. 4

FIG. 5

FIG. 6

FIG. 7

FIG. 8

FIG. 9

FIG. 10

FIG. 11

FIG. 12

FIG. 1 is a perspective view of a seat for a transit vehicle embodying the design of my invention;

FIG. 2 is a rear perspective view of the vehicle transit seat;

FIG. 3 is a rear, elevational view of the vehicle transit seat;

FIG. 4 is a top plan view of the vehicle transit seat;

FIG. 5 is a front elevational view of the vehicle transit seat;

FIG. 6 is a side, elevational view of the vehicle transit seat;

FIG. 7 is a rear perspective view of an alternative embodiment of a seat for a transit vehicle embodying the design of my invention;

FIG. 8 is a rear view of the vehicle transit seat of FIG. 7;

FIG. 9 is a rear perspective view of a second alternative embodiment of a seat for a transit vehicle embodying the design of my invention;

FIG. 10 is a rear elevational view of the vehicle transit seat of FIG. 9;

FIG. 11 is a rear perspective view of a third alternative embodiment of a seat for a transit vehicle embodying the design of my invention; and

FIG. 12 is a rear elevational view of the vehicle transit seat of FIG. 11.

I claim:

The ornamental design of a seat for a transit vehicle, substantially as shown.
